GARMENT HANGER SUPPORT

Richard T. Kennedy, Oaklawn, and Richard S. Latham,
Chicago, Ill., assignors to Ekco Products Company,
Chicago, Ill., a corporation of Delaware

Filed Oct. 8, 1962, Ser. No. 72,030

Term of patent 14 years

(Cl. D80—8)

FIG. 1 is a side elevational view of a garment hanger support showing our new design.

FIG. 2 is a front view thereof.

FIG. 3 is a rear view thereof.

FIG. 4 is a cross-sectional view thereof taken on line 4—4 of FIG. 1.

FIG. 5 is a bottom plan view thereof.

The dominant feature of the design resides in the portion shown in full lines.

We claim:

The ornamental design for a garment hanger support, as shown and described.
